MAGNETIC CORE STRUCTURE

Leopold Mauerer, Chicago, Ill., assignor to Jefferson Electric Company, Bellwood, Ill., a corporation of Illinois

Application July 30, 1942, Serial No. 452,920

9 Claims. (Cl. 175—356)

This invention relates to magnetic core structures, and more particularly to such core structures which are built up of stacked laminations and held in assembled relation by clamping means.

It is of importance in the provision and maintenance of low reluctance core paths in inductance units, transformers and the like which include laminated iron cores, that the laminations thereof be firmly and tightly clamped in such a way that air gaps are minimized or eliminated from the flux paths.

An object of this invention is to provide a magnetic core structure including cooperating stacks of laminations and core clamps adapted to force the stacks into closely abutted relation during assembly, and thereafter to hold the stacks in such closely abutted relation.

Another object of this invention is to provide a magnetic core structure including core clamps or holding elements which not only force the core parts into close assembled relation, but which are also inexpensive and easy to assemble in production.

Further objects and advantages of the present invention will be apparent from the following description, reference being had to the accompanying drawing wherein structures illustrative of the invention are shown.

In the drawing

Figure 1 is a broken elevation of a magnetic core provided with a form of clamping means embodying the present improvements;

Figure 2 is a sectional view taken on line 2—2 of Figure 1 and showing the structure prior to the drawing of the core sections into closely abutting relation;

Figure 3 is a similar section view showing the core sections drawn into closely abutting relation;

Figure 4 is a broken elevation of cooperating core sections provided with a modified form of clamping means;

Figure 5 is a sectional view taken on line 5—5 of Figure 4;

Figure 6 is a similar sectional view showing the core sections drawn into closely abutting relation;

Figure 7 is a broken elevation of cooperating core sections provided with a further modified form of clamping means;

Figure 8 is a sectional view taken on line 8—8 of Figure 7;

Figure 9 is an elevation of a detached clamping member of modified structure;

Figure 10 is a broken elevation of a core with the modified clamping means in position and after deformation to tighten the joint between the core sections; and

Figure 11 is an end elevation of a core showing a pair of the clamping members thereon but prior to deformation of the members.

In Figures 1 to 3 of the drawing a magnetic core is shown comprising two L shaped sections indicated generally by the numerals 10 and 11, each of which is formed of laminations 12. In order to provide a low reluctance core path it is desirable that the contacting surfaces of the core sections 10 and 11 be drawn into and retained in closely abutting relation. For the purpose of uniting the core sections after a winding or windings (not shown) have been assembled thereon and for drawing the sections into such closely abutting relation, two pairs of clamping members are shown in Figure 1. The clamping members are similar and hence one pair only will be described. Each of the clamping members comprises two similar straps 13 which are perforated to receive a rivet 14 by means of which corresponding ends of the straps 13 are attached to one of the core sections and by means of which the laminations of that section may be retained in assembled relation.

The straps 13 span the adjacent joint defined by the surfaces 15 and 16 of the sections 10 and 11 respectively, as shown in Figure 2, and overlie the adjacent portions of the other core section 11. The overlying portions of the straps 13 are provided each with a slot 17 for receiving the ends of a pin 18 which projects from opposite sides of the core section 11. Communicating with the slot 17 are slits 19 formed to provide tongues 20 which are bent outwardly initially from the plane of the respective straps 13. When the core sections 10 and 11 are in the relation shown in Figure 2, the pin 18 is inserted into a receiving aperture formed in section 11 with the ends of the pin projecting beyond the faces of the section.

The straps 13 being of suitable metal, the tongues can be deformed from the normal or initial position shown in Figure 2 into or toward the planes of the respective straps and in being so moved the free ends of the tongues abut the projecting end portions of the pin 18 and force the pin and the core section 11 toward the core section 10. Hence when the tongues 20 have been pressed into or substantially into the plane of the straps 13, the joint surfaces 15 and 16 of the respective core sections will be in intimate

contact one with the other and will be retained in such position which is shown in Figure 3.

The wedging action accompanying the deformation of the tongues 20 of each pair of clamp members not only effects the forcing of the respective joint surfaces 16 and 16 into close contact for insuring a low reluctance path, but the clamps unite the core sections into a rigid unitary structure.

In the modified form of the invention illustrated in Figures 4 to 6 inclusive, U shaped core sections 21 and 22 are shown which are provided with two pairs of clamping straps for uniting the sections and drawing the joint surfaces 23 and 24 thereof into intimate contact. Each pair of clamping members comprises straps 25 which are shown provided with outwardly turned stiffening flanges 26 along the longitudinal edges. As shown in Figure 5 a pair of plates is attached, as by means of a rivet 27, to one of the core sections. The straps 25 span the adjacent joint between the sections and overlies adjacent portions of the other core section. The overlying portions of the straps 25 are provided with slots 28 for receiving a headed abutment pin or rivet 29, the ends of which project from opposite sides of the core section 22. Each strap is provided with an integral tongue 30 which as initially formed is bowed or bent outwardly intermediate its ends as shown in Figure 5. The tongues 30 may be deformed or flattened by pressure applied thereto whereby the free ends of the tongues which abut the projecting ends of the pin 29 force the pin and core section 22 toward the section 21 and thus draw the joint surfaces 23 and 24 into closely abutting relation as shown in Figure 6. The inserted end of the pin or rivet may then be upset as shown in Fig. 6. In the latter figure the outwardly bowed portions of the tongues 30 are shown as somewhat flattened as compared with the illustrations of those members in Figure 5. In this exemplification of the invention also the clamping action is effected by the deformation of the tongues of the clamping members as will be seen.

In Figs. 7 and 8 core sections 31 and 32 are shown provided with clamping members 33, the ends of which are riveted to the adjacent portions of the core sections. The intermediate portion of each clamp member comprises a pair of deformable straps 33^a, which originally are spread apart sufficiently, as indicated by dotted lines in Figure 4, to enable a rivet 34 to be pressed through a perforation in the core sections 32 to further spread the straps apart to the full line position shown in Figure 7. The spreading of the straps 33^a foreshortens the respective clamp members and thus draws the core sections together as in the above described illustrative embodiments of the invention. After the rivet or pin 34 has been pressed into final position for forcing the straps 33^a apart, the entering end of the rivet can be upset as shown in Figure 8.

In Figures 9 to 11 inclusive another form of the improved clamping means is illustrated. In Figure 9 one of the clamps is shown in detached relation and comprises a strap 35 having rivet openings 36 therein whereby a pair of the straps can be riveted to span the joint 37 between core sections 38 and 39 as shown in Figure 11. Each of the straps 35 has perforations 40 formed therein which define longitudinal legs 41 and a transverse intermediate web or bridge 42 which is bowed outwardly initially as shown in Figure 11.

After the straps have been attached in pairs to core sections across the joint or joints thereof that are to be closed the webs 42 are flattened or compressed toward or into the plane of the respective straps. Such deformation of the webs spreads the legs of the respective straps, foreshortening them, and draws the joint surfaces of the core section into intimate contact as illustrated in Figure 10.

10 While the improved clamping members preferably are employed in pairs at all the joints of cooperating core sections that are to be drawn into closely abutting relation, in some instances they may be used singly if desired.

15 It will be observed that in all forms of the invention shown the clamping action is effected by deformation of portions of the clamp member to effect movement of the anchoring means, such as the rivet 14 and pin 18 of Figure 1, or 20 the rivets 33 of Figure 7, one toward the other, thereby forcing the surfaces of the respective joint into intimate contact and minimizing the air gap therebetween. It will also be observed that the clamps when assembled on the core 25 sections and deformed as described provide supports which rigidly unite the assembled core sections. While I have shown and described certain forms of the improved clamps for illustrative purposes, I do not wish to be restricted 30 specifically thereto since changes in detail may be resorted to without departing from the spirit of the invention.

I claim:

1. A magnetic core structure comprising, in 35 combination, cooperating stacks of laminations having surfaces abutted closely together to form joints therebetween and provide a closed magnetic circuit; and core clamping means includ- 40 ing a pair of clamping elements for each joint, the elements of each pair extending across one of said joints on opposite sides of the stacks, fastening means securing the laminations of one of the stacks and one of said pairs of clamping elements together, means extending through the 45 laminations of the other stack and through said pair of clamping elements, each of said clamping elements having an integral deformable portion, deformed into engagement with said last mentioned means and cooperating therewith to hold the laminations and stacks tightly together.

2. A magnetic core structure comprising, in 55 combination, cooperating stacks of laminations and means forcing the laminations of said stacks into tight engagement and holding the laminations in position to provide a closed magnetic circuit, said means comprising clamping elements on opposite sides of the stacks and each extending across portions of each of the stacks, means connecting the clamping elements to the 60 laminations of each of the stacks, and each of said clamping elements having a portion which is bent in such a manner as to hold the stacks of laminations together.

3. In a magnetic core structure having cooper- 65 ating stacks of laminations, means forcing the laminations of the stacks into tight engagement and joining said stacks to provide a low reluctance joint therebetween, said means comprising strap members adjacent opposite sides of the 70 stacks of laminations and having slots therein, means extending through one of the stacks of laminations and the strap members and securing them together, pin means extending through the other of the stacks of laminations and said slots in the strap members, and said strap mem-

bers having integral tongues adjacent said slots and abutting said pin means and deformed to force the stacks of laminations together.

4. A magnetic core structure comprising, in combination, cooperating stacks of laminations and means forcing the laminations of the stacks into tight engagement and joining said stacks to provide a low reluctance joint therebetween, said means comprising strap elements disposed adjacent opposite sides of the stacks and having end openings and longitudinal slots therein, means extending through the laminations of each of the stacks and said end openings and securing the strap elements and laminations together, and means for spreading the mid-portions of the strap elements on opposite sides of said longitudinal slots to foreshorten the strap elements and draw the stacks tightly together.

5. A magnetic core structure comprising, in combination, cooperating stacks of laminations and means joining and effecting close engagement of the laminations of the stacks, said means comprising strap elements adjacent opposite sides of the stacks and having longitudinal slots through the mid-portion thereof, rivets securing the ends of the strap elements to each of the stacks of lamination, and means opening said slots transversely to effect foreshortening of the strap elements.

6. In a magnetic core structure having cooperating core sections having joint surfaces adapted to be drawn into close engagement, means for drawing said sections together comprising strap elements adjacent opposite sides of the sections each comprising separated longitudinal legs and an integral transverse outwardly bowed web joining the mid-portions of said legs and means se-

curing the ends of the strap elements to each of the stacks of laminations, whereby upon deforming said bowed webs toward the plane of the respective legs the latter are spread further apart and foreshortened and the joint surfaces of the core sections are drawn closely together.

7. A magnetic core structure comprising cooperating core sections having surfaces drawn into closely abutting relation to provide low reluctance joints between the sections, clamping means for the stacks at each joint each comprising a strap attached to one of the stacks and spanning the respective joint, a member projecting from the other stack, and a deformed portion carried by said strap and engaging said projecting member for maintaining said joint surfaces together.

8. Means for drawing and holding together joint surfaces of a pair of cooperating core sections, said core sections including in combination therewith, a pair of straps secured to opposite faces of one of said sections and projecting across the joint and over adjacent portions of the other section, abutment members projecting from the latter section, and deformed tongues carried by said straps and abutting said projecting members for forcing said surfaces into close contact.

9. Means for drawing and holding together the joint surfaces of a pair of core sections, said core sections including in combination therewith, a strap spanning the joint, means for anchoring the strap to each section, and a deformable portion carried by the strap which has been deformed to draw the anchoring members one toward the other and whereby the joint surfaces have been forced into closely abutting relation.

LEOPOLD MAUERER.
